UNITED STATES PATENT OFFICE.

JOHN KELLY, OF CHICAGO, ILLINOIS.

WATER-CLOSET.

1,285,216.

Specification of Letters Patent. Patented Nov. 19, 1918.

Application filed May 24, 1918. Serial No. 236,325.

To all whom it may concern:

Be it known that I, JOHN KELLY, a citizen of the United States, residing at Chicago, in the county of Cook and State of Illinois, have invented a new and useful Improvement in Water-Closets, of which the following is a specification.

My invention relates to water-closets of the type employing a valve-device so constructed and arranged as to be automatically operated to connect the flushing-tank with the water-supply when a weight is placed upon the seat of the closet, and to close the water-supply to said tank and open the latter to the bowl of the closet when the weight is removed from said seat. Structures of this general type employ, as a means for operating the valve-device for effecting the above-described operations, a member which, in the depressing of the seat, forces the valve to a position in which the water-supply connects with the flushing-tank, and as they have been hitherto constructed, this member was so positioned that in operating the valve-device, the pressure produced against said member oftentimes was sufficiently great to impair its connection with the seat and oftentimes, when this connection remained secure, pried loose the hinges of the seat.

My primary object is to overcome this objection by a novel, simple, and inexpensive construction of apparatus.

Referring to the accompanying drawings: Figure 1 is a view in side elevation, partly broken, of a water-closet constructed in accordance with my invention, showing the construction in normal position. Fig. 2 is a section taken at the line 2—2 on Fig. 1 and viewed in the direction of the arrows. Fig. 3 is a section taken at the line 3 on Fig. 2 and viewed in the direction of the arrow; and Fig. 4, a view like Fig. 3 showing the parts in the position they assume when the seat of the closet is depressed.

In the particular construction illustrated, the bowl of the apparatus is represented at 5 and may be of the common construction, the portion of the bowl into which the flushing water is introduced being represented at 6. The bowl 5 is equipped with a water connection and valve-housing 7 formed of the hollow section 8 and the tubular section 9. The section 8 is internally screw-threaded at 55 its open end and receives the threaded open

end of the section 9 which extends through the wall of the bowl 5 from the inside thereof at which the section 9 is shouldered, as represented at 10, the connection 7 being thus firmly secured to the bowl preferably 60 with gaskets 11 and 12 interposed therebetween; and the section 9 containing ports 13 in its side-wall communicating with the inlet 6 of the bowl. The section 8 at its outer end is equipped with branches 14 and 65 15 offset relative to each other in a direction lengthwise of the connection 7, which open into each other through the tubular portion 16 of the connection 7 and are adapted for connection, respectively, with a 70 water-supply, as for example the service pipes in a house, and a flushing-tank (not shown), the latter, in practice, being located in a plane above that in which the bowl 5 extends.

The valve device for controlling the filling and discharging of the flushing-tank comprises a stem 17 which reciprocates in the connection 7, its outer end carrying two valves 18 and 19 spaced apart. The valve 18 which preferably, is equipped with a cup-washer 20, is adapted to be moved into and out of a position for closing the branch, and thus the water-supply, to the passage 16 in the connection 7; and the valve 19, which cooperates with a port 21 in a partition 22 between the branch 15 and the inner end of the section 8, is adapted to be moved into and out of a position for closing the branch 15, and consequently the flushing-tank, to the 90 bowl 5. A coiled spring 23 is preferably provided, this spring surrounding the stem 17 between a shouldered part 24 of the connection 7, and a shouldered portion 25 of the valve-stem and serving to insure the 95 shifting of the valve to the position shown in Fig. 3, when the weight on the seat of the closet is removed. The inner end of the stem 17, which is preferably equipped with a roller 26, extends into the interior of the 100 bowl through an opening 27 in the end-wall of the section 9, it being preferred that the stem 17 be equipped with a cup-washer 28 on the inside of the section 9 to prevent leakage of water through the opening 27 in this 105 section.

The section 8 is provided with an upwardly-extending lug 29 containing a pin 30 journaled therein, to the outer ends of which plates 31 are secured, these plates be- 110

ing connected with the seat 32 of the closet, as by screws (not shown) extending through screw-holes 33 in these plates and into the seat and serving to hingedly support the 5 seat.

Supported on the connection 7 at the pin 30 is a plate 34 shown as bifurcated at 35, at which portions the pin 30 passes through it, this plate preferably resting upon the 10 upper edge of the bowl 5, as shown. The forward end of this plate, which is preferably of reduced width, as represented at 36, carries a depending lug 37 containing a pin 38, which pivotally supports a valve- 15 operating rock-member 39 embracing the lug 37 at an opening 40 therein. The rock-member 39 is of bell-crank form, its lower leg 41 bearing against the roller 26 and its upper leg 42 extending into the path of movement 20 of the seat 32 in swinging downwardly.

In the normal position of the parts (Fig. 3), the force of the water from the supply and pressing against the valve-device, aided by the spring 23, holds the valve 18 closed 25 and the seat 32 raised. When a weight is placed on the seat, it swings downwardly on its hinge and rocks the member 39 to the position shown in Fig. 4, thus shifting the valve-device to the left in Fig. 3, opening 30 the flushing-tank referred to in the water-supply and closing this tank to the bowl 5, the flushing-tank thus becoming charged with flushing-water. When the weight is removed from the seat 32, the valve-device 35 automatically opens the flushing-tank to the bowl and closes the pipe 14 to the apparatus and the bowl is flushed, the various parts assuming the positions illustrated in Fig. 3.

It will be noted that by providing the 40 valve-operating means as shown and described, the member which directly engages the valve-device moves against the latter substantially with a straight-line movement, as distinguished from a rubbing action, due 45 to the location of the pivot 38 substantially in the same vertical plane as the point of contact between the member 39 and the roller 26 and thus danger of the parts becoming wedged or otherwise producing un-

due strain which might impair the apparatus, is avoided. 50

While I have illustrated and described a particular embodiment of my invention, I do not wish to be understood as intending to limit it thereto, as the same may be embodied in other forms within the spirit of my invention. 55

What I claim as new and desire to secure by Letters Patent is—

1. In a water-closet, the combination of a 60 bowl, a valve-device for controlling the flushing of the bowl, a hingedly-supported seat arranged to extend above the bowl, a hinged plate supported on said bowl and extending inwardly into the plane of 65 the interior of the bowl, and a rock-member pivoted on the inner end of said plate and arranged to be actuated by the depressing of said seat and in such actuation operating said valve. 70

2. In a water-closet, the combination of a 75 bowl, a valve-device for controlling the flushing of the bowl, a hingedly-supported seat arranged to extend above the bowl, a hinged plate supported on said bowl and 80 extending inwardly into the plane of the interior of the bowl, and a rock-member pivoted on the inner end of said plate, said rock-member being of bell-crank form with one end engaging said valve-device and its 85 other end engaging said seat, whereby it operates said valve-device when said seat is depressed.

3. In a water-closet, the combination of a 85 bowl, a valve device for controlling the flushing of the bowl, a hinged seat arranged to extend above said bowl, the said hinge being located at a point adjacent the outer edge of the bowl, a plate supported on said bowl and hinged at a point adjacent the 90 outer edge of the bowl, said plate extending inwardly into the plane of the interior of the bowl, and a rock-member pivoted on the inner end of said plate and arranged to be actuated by the depressing of the seat and 95 in such actuation operating said valve.

JOHN KELLY.
